UNITED STATES PATENT OFFICE.

CARL ANDERSON, OF CHICAGO, ILLINOIS.

BUTTONHOLE-CUTTER.

No. 920,238.

Specification of Letters Patent.

Patented May 4, 1909.

Application filed May 29, 1908. Serial No. 435,647.

To all whom it may concern:

Be it known that I, CARL ANDERSON, a citizen of the United States, residing at Austin, Chicago, in the county of Cook and State 5 of Illinois, have invented new and useful Improvements in Buttonhole - Cutters, of which the following is a specification, reference being had to the accompanying drawings, forming a part thereof.

10 The purpose of this invention is to provide an improved device of the knife type for cutting button-holes.

It consists of the features of construction shown and described, as indicated in the 15 claims.

In the drawings:—Figure 1 is a perspective view of the device embodying this invention. Fig. 2 is a plan view of the blade stripped of the accessory parts. Fig. 3 is a perspective 20 view of the double - winged gage removed from the blade. Figs. 4 and 5 are views illustrating the manner of assembling the gage and blade showing two successive stages of the process.

25 The blade, A, of thin steel has a straight edge, a^1 , which is blunt, and a cutting edge, a^2 , oblique to the straight edge, the two edges meeting at a point for penetrating the fabric. The upper part of the blade is cut away for 30 reducing it in width above the point at which the divergence of the edges, a^1 and a^2 , affords the width necessary for the maximum size of button-hole for which the tool is designed to be adapted. The blade is provided with a 35 longitudinal slot, a^3 , parallel to the blunt edge, a^1 , said slot extending up beyond the shoulder, a^4 , caused by the reduction of the width and throughout the greater portion of the length of the stem or narrower portion, 40 A⁴, above that shoulder. This blade is provided with a double-winged gage,—that is, a gage which extends on both sides of the blade. It is made of a single piece of sheet metal, B, folded upon itself at the middle 45 point of its length and having the two ends folded oppositely outward at right angles to the wings respectively to form the gage flanges, B¹, B², the device being cut away to reduce it in width at the fold to a neck, B², 50 of the width of the slot, a^3 .

The double-winged gage and the blade are assembled together for engaging the neck, B², in the slot, a^3 , by first entering one of the

flanges, B¹, through the slot, and slightly springing the blade to the amount of its 55 thickness only to permit one edge of the slide to pass between the two wings, as seen in Fig. 4. The assembling is completed by sliding the blade between the two wings of the gage until the neck is in the slot, and then 60 turning the two parts to bring their lateral edges parallel, the flanges, B¹, being then at right angles to the straight edge, a^1 , of the blade. At a little distance below the neck, 65 both wings of the gage are apertured to receive a clamp screw, C, which takes through both said wings and the slot of the intervening blade, a clamp nut, D, being provided at the opposite side for binding the parts together in adjusted position. The margin of 70 the slot, a^3 , is graduated on one side of the blade for reading by the upper end of the wing of the gage upon that side, the graduations being made to correspond to the width of the tapered end of the blade at the under 75 surface of the gage flanges,—that is to say, the width of hole which the blade will cut upon being thrust through the fabric up to the gage. In the drawings, the graduations are numbered from one to eight, each unit of 80 graduation corresponding to one-eighth of an inch of width of the exposed blade or width of hole which will be cut. For convenience in adapting the tool for measuring also the distance from button-hole to button-hole, 85 the opposite surface of the blade from that having the button-hole width graduations above mentioned is graduated along the straight edge, a^1 , in inches and fractions of an inch commencing from the upper end. 90

I claim:—

1. A button-hole cutter comprising a tapering blade having a longitudinal slot, in combination with a double-winged gage made of one piece folded upon itself and reduced at the fold to form a neck of the width of the slot, and a clamp screw taking through both wings and the slot. 95

2. A button-hole cutter comprising a tapering blade having one edge blunt and the other sharp for cutting, and having a longitudinal slot parallel to the blunt edge, in combination with a double-winged gage consisting of a single piece of metal folded upon itself and reduced at the fold to form a neck 100 of the width of the slot and engaged therein, 105

the two wings being oppositely flanged at the ends at right angles to the length to form stops upon opposite sides of the blade, and a clamp screw taking through the wings and the slot for clamping the parts in adjustable position.

In testimony whereof, I have hereunto set

my hand at Chicago, Illinois, this 15th day of May, 1908.

CARL ANDERSON.
